UNITED STATES PATENT OFFICE.

CHRISTOPHER D. McDONALD, OF VANCE, COLORADO.

REVOLVER.

SPECIFICATION forming part of Letters Patent No. 652,625, dated June 26, 1900.

Application filed February 9, 1900. Serial No. 4,648. (No model.)

To all whom it may concern:

Be it known that I, CHRISTOPHER D. McDONALD, of Vance, in the county of San Miguel and State of Colorado, have invented 5 a new and useful Improvement in Revolvers, of which the following is a specification.

My invention is in the nature of an improvement upon the revolver for which I have made application for Letters Patent of the 10 United States, Serial No. 725,091, which application was filed July 25, 1899, and allowed September 29, 1899. In this application I described and claimed a revolver in which the handle portion is provided with rigidly-attached upper and lower extensions inclosing 15 the cylinder-space, and the barrel is hinged on a vertical axis between the forward ends of said rigid extensions and bears the revolving cylinder, which swings out when the barrel is deflected about said joint at the two forward extensions of the handle. My present 20 invention employs this same general principle of construction, but provides an improved means of articulation, as will be hereinafter more fully described with reference 25 to the drawings, in which—

Figure 1 is a side view, partly broken away. Fig. 2 is a plan view with the barrel turned to one side in dotted lines. Fig. 3 is a 30 partial longitudinal section on line 3-3 of Fig. 2. Fig. 4 is a transverse section through line 4-4; and Figs. 5 and 6 are plan views of the rear portion of the barrel, partly broken away to show the means for jointing the barrel to 35 the handle extensions.

In the drawings, A represents the barrel, carrying the cylinder C, and B is the handle, having rigid forward extensions b and b', inclosing the cylinder, and to the forward ends 40 of which extensions the barrel is jointed about a vertical axis, as shown and described in my former application referred to.

In my present invention one side of the rear end of the barrel is made with a lateral 45 projection a, in which is formed an elongated chamber opening at the upper edge of the barrel, containing a horizontal locking-bar a', having a thumb-piece or lip a³ extending through a notched portion of the barrel out 50 to the edge of the same. In the elongated chamber, beneath the locking-bar a', is an el-

liptical spring a², which makes the bar spring-seated, normally holding it up in locking position to prevent the barrel from being turned on its axis of articulation, but capable of being depressed by the thumb, so as to allow the rear end of the barrel to pass under the forward extension b of the handle. 55

The articulated joint of the barrel is formed at the lower side by a simple screw f, connecting the lower extension b' of the handle to the lower lug of the barrel. At the upper side, however, there is a peculiarly-formed joint, as follows: The upper extension b of the handle is recessed at b² on its upper side, 60 which portion passes under an overhanging part a¹ on the rear end of the barrel. The lower side of the extension b is formed at its extreme end with a circular boss b³, which forms the center bearing of the joint and is 65 locked in a chamber b⁴ in the rear end of the barrel, as follows:

A movable block d has a concave front end fitting the boss b³ on the extension b. This block d is slipped into the right-angular recess in the top of the barrel behind the boss b³ by being first inserted through the side opening d' and is then pushed up to the position shown in Fig. 5. A locking-slide e, Fig. 5, is then slipped sidewise into the opening d' and when fully in is fastened by a screw e', as in Fig. 6, and retains the block d behind the boss or joint-bearing b³. To take the revolver to pieces, the screw e' is taken 70 out and the slide e and block d removed 75 through the outlet d', and the screw f of the lower joint being removed the boss or bearing b³ can be drawn back and taken out through the opening d'. 80

When the barrel is in true alinement, the 85 long locking-bar a' is forced up by its subjacent spring a² and by bearing against the side of the upper extension b holds the barrel firmly in alinement, so that it cannot be bent on its joint, and the long bearing which the 90 bar a' affords makes a very strong lock and holds the barrel firmly in alinement.

In breaking the revolver for ejecting the shells and reloading the handle is taken in the right hand and the barrel in the left, with 95 the thumb of the left hand resting upon the lip a³ of the spring-seated locking-bar, and 100

it will be seen that all the parts are so organized as to enable this action to be quickly and most conveniently effected.

Having thus described my invention, what I claim as new, and desire to secure by Letters Patent, is—

1. A revolver having a handle with a rigid extension beyond the cylinder, and formed with a pivot-boss on its lower side at the end, a barrel having a recessed upper surface at the rear end with a side outlet, a detachable bearing-block adapted to be introduced through this side outlet and pushed up to the boss, and a laterally-inserted locking-slide for the bearing-block substantially as described.

2. An articulated joint for a revolver, con-

sisting of a barrel having an overhanging rear end a^1 and a right-angularly-recessed chamber beneath it with lateral outlet, a handle extension b with recessed upper surface b^2 and boss b^3 , and the detachable bearing d arranged to be inserted through the lateral outlet and pushed up to contact against the boss, and the locking-piece e inserted laterally behind the bearing d substantially as and for the purpose described. 20

In testimony whereof I have signed my name to this specification in the presence of two subscribing witnesses.

CHRISTOPHER D. McDONALD.
